UNITED STATES PATENT OFFICE

169,563

COMBINED HANDKERCHIEF BOX AND TIE RACK

Percy W. Robinson, Toledo, Ohio

Application November 29, 1952, Serial No. 22,495

Term of patent 14 years

(Cl. D33—8)

To all whom it may concern:

Be it known that I, Percy W. Robinson, a citizen of the United States, residing at Toledo, State of Ohio, have invented a new, original, and ornamental Design for a Combined Handkerchief Box and Tie Rack, of which the following is a specification, reference being had to the accompanying drawing, forming a part hereof.

Fig. 1 is a top plan view of a combined handkerchief box and tie rack, showing my new design.

Fig. 2 is a front elevational view;

Fig. 3 is a sectional view at the line 3—3 on Fig. 2; and

Fig. 4 is an end elevational view.

I claim:

The ornamental design for a combined handkerchief box and tie rack, as shown.

PERCY W. ROBINSON.
